UNITED STATES PATENT OFFICE.

PERLEY L. KIMBALL, OF BELLows FALLS, VERMONT, ASSIGNOR TO THE VERMONT FARM MACHINE COMPANY, OF BELLows FALLS, VERMONT, A CORPORATION OF VERMONT.

SPEED-INDICATOR.

1,313,389.

Specification of Letters Patent.

Patented Aug. 19, 1919.

Application filed June 18, 1919. Serial No. 305,112.

To all whom it may concern:

Be it known that I, PERLEY L. KIMBALL, a citizen of the United States, residing at Bellows Falls, in the county of Windham and State of Vermont, have invented a certain new and useful Improvement in Speed-Indicators, of which the following is a full, clear, and exact description.

This invention relates to audible speed indicators, for use on machines where it is desirable to maintain a given speed and to audibly apprise the operator either when the speed is exceeded or unduly diminished; and while the present invention is primarily 15 designed for use in connection with centrifugal cream separators, it is to be understood that its use is not so limited.

In speed indicators of the character in question, it is common to use a bell or gong 20 having a gravity striker, such as a metal ball, so arranged that when the machine to which the device is applied is running below normal, it will sound an alarm, while remaining silent at other times.

The present invention is in the nature of an improvement on the speed indicator forming the subject of my case filed October 3, 1918, Serial No. 256,662, and the invention consists in certain structural and 30 operative features whereby the efficiency of the indicator is enhanced, same comprising a novel construction and arrangement of the ball scoops or cups, and the offsetting of the rim of the bell or gong to form pockets 35 into which the ball scoops or cups extend so that their inner surfaces will come substantially on a line or in a plane with the inner surface of the rim of the bell at the ends of the scoops or cups, thereby making 40 a smooth even floor for the ball to roll over, and means to interlock the bell and scoops or cups to prevent independent movement thereof, as I will proceed now to explain and finally claim.

In the accompanying drawings illustrating the invention, in the several figures of which like parts are similarly designated, Figure 1 is a sectional elevation showing the indicator applied to the end of a rotary shaft, the section of the bell being taken substantially in the plane of line I—I of Fig. 2. Fig. 2 is a rear elevation with the back-plate removed. Fig. 3 is a transverse section taken substantially in the plane of

line III—III, Fig. 2, but inverted with relation to Fig. 2. Fig. 4 is a sectional elevation of the silencer scoop or cup, and Fig. 5 is a top plan view thereof. Fig. 6 is a transverse section showing the details of connection of the arms with the scoop or cup of Fig. 3.

The bell or gong 1 is a cup-shaped structure, circular in outline, excepting that its rim 2 has the offset portions 3 and 4 preferably arranged opposite one another to form 65 pockets for the reception of the striker or ball scoops or cups 5 and 6, and of such depth and with the scoops so arranged therein that the opposite surfaces of the scoops will be substantially in line or on a 70 level with the remainder of the rim and so that when the striker or ball rolls off of the scoop or cup onto the rim, it will do so on a level and without unnecessary jar. The scoop or cup 5 has the lateral ball-confining flanges 7, and its ends are provided with V-shaped notches 8, as shown more in detail in Fig. 3, the apexes of the notches pointing toward the center of the scoop or cup. These notches cause the ball to roll 80 toward and strike into the center of the radial groove 9 of a center block 10 applied to the scoop or cup, and thereby the ball is prevented from bobbing about before coming to rest within the scoop. As will be 85 seen, the scoop or cup is a segment of a circle, whose center is the axis of the bell. The block 10 is a frustum of a pyramid, the opposite faces of which are provided with the grooves 9. These grooves, as al- 90 ready intimated, serve to center the striker or ball and assist in its proper escape from the scoop or cup in the revolution of the bell. In the preferred construction the block is a separate piece, machined all over, and 95 held in rigid relation to the scoop or cup by means of the arms 11 and 12, the lower ends of which are made with tenons 13 and 14 socketed in the sides of the block, as shown in Fig. 6, and the ends of these tenons 100 extend through the scoop or cup and are clenched on the outside, as shown in Figs. 1; 2 and 4. This makes a very firm and accurate holding of both the cup and the block. The separate block has the further 105 advantage that the mechanical accuracy of the tapered sides or angles is much more easily obtained; and the accuracy necessary

to cause the bell to stop ringing at practically the same number of revolutions per minute in every bell manufactured when tested in both directions of rotation has been 5 found to be much greater by the machining method than by the press-forming method heretofore employed. The block is used in only one of the scoops or cups, and the bell is sounded only once in each complete revolution. This decreases the cost of each bell, 10 and also simplifies the counting in cases where users count the strokes of the bell rather than being guided by the stopping of its ringing.

15 The opposite ends of the arms 11 and 12 have secured to them the scoop or cup 6, and this scoop or cup is like the one previously described, excepting that it is not necessary or even advisable to employ a block 20 in it or to notch its ends. Instead the bottom of this scoop or cup is covered with a suitable fabric 15, that will serve to deaden the noise of the falling ball. This surfacing material may be any suitable form of 25 adhesive fabric, fastened down to the scoop or cup and preferably having its ends folded over the edges of the scoop or cup and fastened down by any suitable metal staples 16. Instead of providing the ends of this 30 scoop or cup with V-shaped notches, these ends may be made square and the silencer or fabric 15 is carried over these ends, as already stated. This fabric makes a smooth non-vibrant jacket or cushion which is very 35 effective.

The bell is rigidly connected with the arms 11 by the provision of tongues 17 extending through openings 18 in the bell. The bell, the arms 11 and 12 and the back- 40 plate 19 are connected by means of a stay-bolt 20, one end 21 of which is screw threaded and screwed into a hub 22 which may engage with the end of a shaft 23 by means of the set-screw 24. The shaft 23 45 may be the main driving shaft of the machine on which the indicator is used, and it may be power driven, or, as shown in Fig. 1, may have the crank handle 25 by which it may be hand driven.

50 In order to prevent as far as possible tampering with the indicator, the outside or exposed end of the stay bolt 20 may be upset or clenched as indicated at 26, Fig. 1.

By fixing the relation of the arms 11 and 55 12 of the scoop and preventing their turning upon the center stud or stay-bolt when screwing the bell on or off, insures the continuous operation of the sounding as long as the indicator is in motion.

60 The operation would seem to be apparent from the foregoing description, but it is to be noted that the two scoops or cups have distinct and independent functions. That one of the scoops or cups which has the 65 grooved block catches the ball and throws

it onto the bell to make the proper sound, while that one having the cushioned surface catches the ball after it has rung the bell and allows the ball to roll through noiselessly to the scoop with the block in it, which 70 carries the ball upwardly with the rotation of the bell until it is in position to fall off and strike the bell beyond the end of the cup once in each revolution of the bell.

It will be seen that by the use of the silencer, the bell is practically noiseless, excepting of course, when intentionally and specifically rung by the dropping of the ball 75 from the scoop or cup.

The striker or ball may be of any usual 80 or approved construction and configuration, and I have herein shown it as a sphere 27. This striker or ball is shown by a broken line circle in Fig. 1, in order to expose other 85 features of the invention.

Variations in the details of construction and arrangement of parts are deemed to be 90 permissible within the principle of the invention and the scope of the claims herein-after made.

What I claim is:

1. In a speed indicator of the bell and ball variety, a ball scoop or cup having a central block and opposite ends adapted to 95 guide the ball to the block.

2. In a speed indicator of the bell and ball variety, a ball scoop or cup having V-notched terminals and an intermediate block provided with substantially radial grooves.

3. In a speed indicator of the bell and ball 100 variety, a ball scoop or cup having V-notched ends and a central block of frusto-pyramidal form, the opposite faces of the block having grooves aligned with the notches 105 for guiding the ball.

4. In a speed indicator of the bell and ball variety, a ball scoop or cup having a central block and supporting arms for said scoop or cup positively engaging and connecting both 110 the scoop or cup and its block.

5. In a speed indicator of the bell and ball variety, a ball scoop or cup having a central block and supporting arms for said scoop or cup having tenoned ends interlocked with the block and scoop or cup and 115 rigidly connecting them.

6. In a speed indicator of the bell and ball variety, a scoop or cup mounted upon fixed arms and adapted to throw the ball into contact with the bell, and a cushioned scoop or 120 cup fixed at the opposite ends of said arms and adapted to return the ball to the other scoop or cup.

7. In a speed indicator of the bell and ball variety, a non-sounding scoop or cup for engaging the ball provided with a cushioned surface positively fixed thereto.

8. In a speed indicator of the bell and ball variety, the combination of a ball-throwing scoop or cup, rigidly arranged arms sup- 130

porting the same, a bell, and tongues on one of the scoop-supporting arms rigidly engaging holes in said bell.

9. In a speed indicator of the bell and ball variety, a bell having an offset in its rim, and a ball scoop or cup rigidly supported in said offset.

10. A speed indicator of the bell and ball variety, having a rimmed bell provided with opposite offsets in its rim, arms rigidly connected with said bell, ball scoops or cups

rigidly attached to the opposite ends of said arms, and ball engaging surfaces substantially level with those portions of the bell between the offsets.

15 In testimony whereof I have hereunto set my hand this 16th day of June A. D. 1919.

PERLEY L. KIMBALL.
